DESIGN.

E. HARDY.

MANTEL PIECE.

No. 16,579.

Patented Mar. 23, 1886.

UNITED STATES PATENT OFFICE.

EMILE HARDY, OF ANDOVER, ASSIGNOR TO THE CRAIGHEAD & KINTZ MANUFACTURING COMPANY, OF BALLARD VALE, MASSACHUSETTS.

DESIGN FOR A MANTEL-PIECE.

SPECIFICATION forming part of Design No. 16,579, dated March 23, 1886.

Application filed October 27, 1885. Serial No. 181,113. Term of patent 14 years.

To all whom it may concern:

Be it known that I, EMILE HARDY, of Andover, in the county of Essex and State of Massachusetts, have invented a certain new and original Design for a Mantel-Piece, of which the following is a specification.

The chief features of my design are the side pieces or pilasters ornamented with infant figures, scroll-like figures, and foliate figures, the base-pieces and capitals of such pilasters, an entablature intermediate of the pilasters ornamented with infant figures, and moldings extending continuously above the entablature.

15 I will describe a mantel-piece embodying my design, and then point out the novel features in the claims.

The accompanying illustration is a front view of a mantel-piece embodying my design.

20 A designates the side pieces of the mantel-piece. They are made in the form of pilasters, having base-pieces or pedestals a , ornamented on the face with entablatures a' , having delineated upon them scroll-like figures, 25 with a boyish figure in the center. Above the base-piece is an ogee molding, a^2 , surmounted by a fillet or angular molding, a^3 . The body portion of the side pieces or pilasters A are ornamented with panels a^4 , which have 30 outer moldings, a^5 . One of these panels has on the face and within the moldings a^5 figures in relief of a boy standing on an urn, another boy climbing up the urn, a third boy above the others, and scroll and foliate figures. The

35 other panel, a^4 , has on the face an urn with a boy sitting on it and a parrot perching on it, another boy higher up, birds, and foliate and scroll-shaped figures. Immediately above the panels a^4 are projecting panels a^6 , having

flat border-like moldings, and foliate embellishments on the face within the moldings. Above and below the panels a^6 are moldings a^7 . Above the panels a^6 are panels a^8 , of larger size and greater projection. The panels a^6 a^8 40 form capitals to the pilasters.

45 Between the pilasters A a large entablature, B, is located. On a panel which is arranged upon it are delineated various infant figures, two in the act of flying, one in the act of playing upon the tambourine, another drumming, and another waving a plume.

50 Above the panels a^8 and entablature B is a molding, C, consisting of small flower-like figures in niches or recesses. Above the molding C is a molding, D, consisting of a flat surface ornamented with projecting blocks. Immediately above the molding D is a flat molding, E. This is surmounted by a foliate molding, F, embellished with pendants f . Moldings G are arranged above the molding F.

55 60 What I claim as my invention, and desire to secure by Letters Patent, is—

1. In a design for a mantel-piece, the panels of the side pieces or pilasters ornamented with infant figures, scroll-like figures, and foliate figures, and the base-pieces and capitals of such pilasters, substantially as shown and described.

55 70 2. In a design for a mantel-piece, the pilasters and intermediate entablature embellished with infant figures and moldings extending continuously above the same, substantially as shown and described.

EMILE HARDY.
